BEND ALIGNING AND ANGLE MEASURING DEVICE FOR LARGE DIAMETER PIPE SECTIONS

George D. Page, Oskaloosa, Iowa

Application May 31, 1956, Serial No. 588,414

6 Claims. (Cl. 33—46)

This invention relates to the art of bending and aligning the ends of sections of large diameter pipe of the kind which are finally placed, for the most part, underground, and the main object is the provision of a novel, useful and practical bend aligning and angle measuring device to facilitate the installation of the pipe and to lessen substantially the consumption of time in carrying out the installation, with consequent economies.

The above broad as well as additional and more specific objects will be clarified in the following description wherein reference numerals refer to like-numbered parts in the accompanying drawings. It is to be noted that the drawings are intended solely for the purpose of illustration and that it is therefore neither desired nor intended to limit the invention necessarily to any or all of the exact details of construction or operation shown or described except insofar as they may be deemed essential to the invention.

Referring briefly to the drawings, Fig. 1 is a fragmentary plan view of one end of a pipe of the kind above referred to, equipped with an embodiment of the present invention.

Fig. 2 is an end elevational view of the same.

Fig. 3 is a sectional view taken on the line 3—3 of Fig. 1.

Fig. 4 is a sectional view taken on the line 4—4 of Fig. 1.

Fig. 5 is an enlarged fragmentary view similar to Fig. 2, with parts broken away and partly in section.

The present invention which consists in an attachment in duplicate adapted to be mounted on each of the straight end sections of a bent pipe, will first be described, and then the manner of operation and use of the same will be set forth.

Referring in detail to the drawings, the numeral 10 indicates a length or section of large diameter pipe of the type mentioned, which has been bent by a bending machine to provide a bend, predetermined by the surveyor, to accommodate the pipe to join up with the next forward pipe section. Such bends as usually applied to a pipe section begin at a point not less than five feet from the adjacent end of the section. The bending machine advances in the direction of the pipe line, generally at a considerable distance ahead of the crew which lines up and welds all the sections together. As a result, the crew frequently find that the pre-bent pipe which they are about to weld together does not have its bend at an angle close enough to the required angle to connect properly with the next forward section, so that the pipe must be again worked upon by the bending machine. This obviously entails an unnecessary and costly delay, as the crew must remain idle while the bending machine is brought back to correct the bend, and the entire procedure is thus retarded at considerable cost. The use of the present invention assures that the pipe will be properly bent for proper line-up end to end and thus eliminate such uneconomical delays.

The device of the present invention consists of two

2

identical attachments 11 and 12; hence but one will be described in detail but like reference numerals indicating similar parts will be applied to both.

The attachment comprises a base composed of two spaced arcuate members, that is, side members, 13 and 14 which are curved to conform to the contour of the pipe and have a length of arc of substantially 180 degrees, together with two end members 15, all together forming a frame of the base. The arcuate members 13 and 14 are angle-shaped with the upright flanges 16 thereof having arcuate slots 17 therein. A carriage 18 has outward extensions or rollers 19 riding in the slots 17. The carriage is likewise arcuate and is elongated through an arc somewhat in excess of 90 degrees. Near the upper end of the carriage a sighting post 20 is mounted and extends radially therefrom. At an arcuate distance of 90 degrees from the post 20, a second similar sighting post 21 is similarly mounted.

Adjacent the top sighting post 20 a bubble level 22 is mounted on the carriage, to indicate when the carriage is so positioned that the post 20 is truly in a vertical plane through, as will become apparent below, the axis of the straight end portion of the pipe. On the other side of the carriage and in alignment with the post 20 and the bubble of the level when the latter indicates that the post 20 is in the said vertical plane, is a notched indicator or pointer 23 positioned close to the underside of the base frame of the device and it is secured by its upper deformed end to the carriage. The entire device is mounted on the pipe 10 merely by positioning it thereon substantially as shown and it will remain in position by gravity. If desired, a small counterweight, not shown, may be attached to the upper end of the frame 10, or the undersides of the frame may be wholly or partly coated with friction enhancing means such as, for example, a rubber compound, not shown. A thumb screw locking means, shown at 24, is provided to releasably lock the carriage against longitudinal movement.

It is now apparent that, assuming the carriage to be positioned in its track so that the post 20 is truly vertical, the post 21 will then be truly horizontal. If the two attachments 11 and 12 are thus mounted on the straight end portion 10a of a bent pipe section, with both posts 20 truly vertical, these posts will lie in a vertical plane 40 through the axis of the pipe portion 10a. If, then, the pipe is marked at the spot indicated by each pointer 23, and the attachments are removed, a line may be drawn or painted between the two points, which will lie in the said vertical plane through the axis of the pipe portion 10a and will indicate the true uppermost linear portion of the pipe. In other words, the section can be properly lined up for welding when this line is uppermost. Thus, since, as above set forth, the pipe has been bent some time before the pipe line-up-and-weld crew reaches 45 it, it will be a simple matter to position the section properly, for often it is extremely difficult if not impossible to be certain that eye-work alone has judged correctly the top of the pipe as it is to be joined, in pipes of such large diameter, regardless of whether it is a regular bend or a combination bend.

To check the correctness of a bend, the device is used as follows. It is well known that after a bent section has been lined up with the next rearward bend, it is necessary that the forward straight portion of the section 50 point in the proper direction to line up with the next forward bend. If a third post, not shown, is positioned vertically at a considerable distance, say several hundred feet, ahead of the pipe section in proper position, that is, in a position into which the section end 10a is to point 55 when welded, by sighting between the three posts (the distant post and the two posts 20), the degree of error, if any, in the direction or angle of the bend can be

readily determined. Assuming that the posts 20 are positioned four feet apart and that the sighter is positioned four feet rearward of the rearward post 20 and that the distant post is 300 feet away, the angle of error in the bend may be readily calculated, and if it is greater than the allowable error for practical purposes the bend must be corrected.

At any position along the pipe line between bends, through a distance of, say, 300 feet, the average line of the bottom of the trench which is to receive the pipe, will usually be parallel with the ground. Also, since the distant pole (which has every odd foot painted red and every even foot painted white) is placed five feet from the trench, one degree of horizontal error is equal to the distance of the pole from the trench. By sighting the horizontal posts of the attachments 11 and 12 with the distant pole, it is thus obvious that the proper horizontal position of the section portion 10a can also be readily checked.

It is not believed necessary to enter into a discussion of engineering or mathematical calculations which may be involved in the application of the present device, as they are well known to those involved in their application and do not form a part of the invention as illustrated in the drawings.

I claim:

1. A device of the class described adapted to be mounted on the straight end of a pipe having a bend spaced from said end, comprising an arcuate base having the conformation of the pipe and an arcuate length of approximately 180 degrees, said base having an arcuate carriage concentric with the base longitudinally movably mounted thereon, said carriage having a radial post near one end thereof and a second radial post longitudinally spaced ninety degrees from the first-named post, and means for releasably locking the carriage against longitudinal movement on the base, the device being adapted to be mounted concentrically on the pipe with one of said posts in approximately vertical position whence by movement of the carriage said one of said posts may be positioned in vertical position, said base including parallel arcuate side members having longitudinal slots therein, said carriage having outward projections registering in said slots.

2. A device of the class described adapted to be mounted on the straight end of a pipe having a bend spaced from said end, a first attachment comprising an arcuate base having the conformation of the pipe and an arcuate length of approximately 180 degrees, said base having an arcuate carriage concentric with the base longitudinally movably mounted thereon, said carriage having a radial post near one end thereof and a second radial post longitudinally spaced ninety degrees from the first-named post, and means for releasably locking the carriage against longitudinal movement on the base, the device being adapted to be mounted concentrically on the pipe with one of said posts in approximately vertical position, a second attachment identical to said first attachment similarly mounted on said end of the pipe and spaced from said first named attachment, the base of each of said attachments including parallel arcuate side members having longitudinal slots therein, the carriages having outward projections registering in said slots.

3. A device of the class described adapted to be mounted on the straight end of a pipe having a bend spaced from said end, comprising an arcuate base having the conformation of the pipe and an arcuate length of approximately 180 degrees, said base having an arcuate carriage concentric with the base longitudinally movably mounted thereon, said carriage having a radial post near one end thereof and a second radial post longitudinally spaced ninety degrees from the first-named post, and means for releasably locking the carriage against longitudinal

movement on the base, the device being adapted to be mounted concentrically on the pipe with one of said posts in approximately vertical position whence by movement of the carriage said one of said posts may be positioned in vertical position, said carriage having a bubble level thereon spaced laterally from said one of said posts and having the bubble thereof adapted to be centered in the intersection of a plane through one of said posts and the axis of curvature of the carriage with a plane at right angles to said first-named post whence said one of said posts is vertical and the other of said posts is horizontal when the bubble is centered in the level.

4. A device of the class described adapted to be mounted on the straight end of a pipe having a bend spaced from said end, comprising an arcuate base having the conformation of the pipe and an arcuate length of approximately 180 degrees, said base having an arcuate carriage concentric with the base longitudinally movably mounted thereon, said carriage having a radial post near one end thereof and a second radial post longitudinally spaced ninety degrees from the first-named post, and means for releasably locking the carriage against longitudinal movement on the base, the device being adapted to be mounted concentrically on the pipe with one of said posts in approximately vertical position whence by movement of the carriage said one of said posts may be positioned in vertical position, said carriage having a bubble level thereon spaced laterally from said one of said posts and having the bubble thereof adapted to be centered in the intersection of a plane through one of said posts and the axis of curvature of the carriage with a plane at right angles to said first-named post whence said one of said posts is vertical and the other of said posts is horizontal when the bubble is centered in the level.

5. A device of the class described adapted to be mounted on the straight end of a pipe having a bend spaced from said end, a first attachment comprising an arcuate base having the conformation of the pipe and an arcuate length of approximately 180 degrees, said base having an arcuate carriage concentric with the base longitudinally movably mounted thereon, said carriage having a radial post near one end thereof and a second radial post longitudinally spaced ninety degrees from the first-named post, and means for releasably locking the carriage against longitudinal movement on the base, the device being adapted to be mounted concentrically on the pipe with one of said posts in approximately vertical position whence by movement of the carriage said one of said posts may be positioned in vertical position, a second attachment identical to said first attachment similarly mounted on said end of the pipe and spaced from said first attachment, the carriage of each of said attachments having a bubble level thereon spaced laterally from said one of said posts and having the bubble thereof adapted to be centered in the intersection of a plane through said one of said posts and the axis of curvature of the carriage with a plane at right angles to said first-named post whence said one of said posts is vertical and the other of said posts is horizontal when the bubble is centered in the level.

6. A device of the class described adapted to be mounted on the straight end of a pipe having a bend spaced from said end, a first attachment comprising an arcuate base having the conformation of the pipe and an arcuate length of approximately 180 degrees, said base having an arcuate carriage concentric with the base longitudinally movably mounted thereon, said carriage hav-

ing a radial post near one end thereof and a second radial post longitudinally spaced ninety degrees from the first-named post, and means for releasably locking the carriage against longitudinal movement on the base, the device being adapted to be mounted concentrically on the pipe with one of said posts in approximately vertical position whence by movement of the carriage said one of said posts may be positioned in vertical position, a second attachment identical to said first attachment similarly mounted on said end of the pipe and spaced from said first attachment, the carriage of each of said attachments having a bubble level thereon spaced laterally from said one of said posts and having the bubble thereof adapted to be centered in the intersection of a plane through said one of said posts and the axis of curvature 15 of the carriage with a plane at right angles to said first-named plane whence said one of said posts is vertical and the other of said posts is horizontal when the bubble is centered in the level, the carriage of each of said

attachments having a pointer thereon extending from one side thereof positioned in said first-named plane and near the lower edge of the base to indicate a point on the top of the pipe in the vertical plane of the pipe axis when said one of said posts is positioned vertically as aforesaid so that a mark may be placed on the pipe at that point.
